W. C. MERRILL,
APPARATUS FOR VULCANIZING,
APPLICATION FILED JULY 15, 1915.

Patented Dec. 10, 1918.

UNITED STATES PATENT OFFICE.

WILLIS C. MERRILL, OF BOSTON, MASSACHUSETTS, ASSIGNOR, BY MESNE ASSIGNMENTS, TO THE MERRILL PROCESS COMPANY, OF BOSTON, MASSACHUSETTS, A CORPORATION OF MASSACHUSETTS.

APPARATUS FOR VULCANIZING.

1,287,071.

Specification of Letters Patent. Patented Dec. 10, 1918.

Application filed July 15, 1915. Serial No. 40,076.

To all whom it may concern:

Be it known that I, WILLIS C. MERRILL, of Boston, in the county of Suffolk and State of Massachusetts, have invented certain new and useful Improvements in Apparatus for Vulcanizing, of which the following is a specification.

My invention relates to a method of and apparatus for vulcanizing rubber goods.

10 The main object of my invention is the use of a circulating heating fluid having a boiling point above 212° F. and a carbonizing point higher than the temperature required for the proper vulcanization of the 15 goods under treatment, and by the use of such circulating heating fluid high temperatures are produced, while the pressure of the circulating heating fluid is negligible.

Another object is to control the temperature 20 of the circulating heating fluid so that when it reaches a predetermined maximum point suitable for the proper vulcanization of the goods then any further increase in temperature of said circulating heating fluid 25 through the vulcanizer is cut off until the temperature of the circulating heating fluid drops to the predetermined maximum point, when the apparatus employing my improved method will automatically operate to circulate 30 the circulating heating fluid through the vulcanizer, and will so continue until the temperature of the circulating heating fluid again reaches the predetermined maximum point when the operation is repeated as 35 above described.

These and other objects are carried out by the apparatus hereinafter described and illustrated in the claims, and in which my improved method of vulcanizing is carried 40 out.

In the accompanying drawings which illustrate a construction in which my improved method is carried out:

Figure 1 is a side elevation with the vulcanizer in section and in which my improved method is employed.

Fig. 2 is a detail sectional view of the thermostatic device controlling the flow of fuel to the gas or fuel burner.

50 Fig. 3 is a longitudinal view partly in section through the upper end of the vulcanizer on the line X—X, Fig. 1, and showing the upper plate for diverting and guiding the

flow of the circulating heating fluid, with the heating coil omitted.

55

Like letters of reference refer to like parts throughout the several views.

The heating medium used in this apparatus preferably is a petroleum or other suitable oil unaffected by high temperatures and of high carbonizing point and is supplied to the apparatus from the supply or expansion tank 1 through the pipe 2 and is drawn in and forced by the pump 3 into the pipe 6 thence into the heater 8 where the pipe 6 is 60 coiled as shown at 7 to increase the heating surface thereof. The products of combustion pass out from the heater through the stack 24. The heated oil then passes out into the pipe 6 and through the thermostatic device 11 into the pipe 13 and thence into the jacket 14 of the vulcanizer. The circulating heating oil passes, as indicated in Fig. 3 by the arrows, around the vulcanizing chamber 27 to the ports 44 of the oil diverting plate 41 and down through said ports 44 to the ports 45 in the oil diverting plate 42 and thence through the ports 46 in the oil diverting plate 43 to the bottom of the jacket 14 around the vulcanizing chamber 27 and 65 thence out through the pipe 15 through the thermostatic device 16 to the pump 3 so that the circulation of this heated oil is continued through the apparatus by means of the pump 3. The burner 9 of the gas heater 8 is connected by the pipe 10 to the fuel supply tank 12 and located in said pipe 10 is a thermostatic device 11 shown in Fig. 2 for controlling the flow of fuel from the fuel supply tank 12 to the burner 9 of ordinary 70 construction, so that as long as the temperature of the circulating heating fluid in the pipe 6 is below a predetermined point the fuel will flow to the burner 9, but upon the temperature of the circulating heating fluid in the pipe 6 is below a predetermined point the thermostatic device 11 will operate to shut off the supply of fuel to the burner 9, and upon the temperature of the circulating heating fluid flowing 75 through the pipe 6 reaching a predetermined point the thermostatic device 11 will operate to shut off the supply of fuel to the burner 9, and upon the temperature of the circulating heating fluid flowing through the pipes 6 and 13 falling below a predetermined maximum point the thermostatic device 11 will automatically operate to allow the fuel supply to again pass to the burner 9. This thermostatic device consists 80 of the box 11 with the usual spring 39 to

70

which is attached the stem 38 carrying the valve 37 which controls the flow of fuel through the pipe 10 to the burner 9. In the installation of an apparatus of this class for 5 vulcanizing the thermostatic device 11 is set to operate at a predetermined maximum temperature, say 275° F. for soft rubber goods and 305° F. for hard rubber goods, which are about the maximum temperatures 10 for properly heating soft and hard rubber goods without injury respectively, and as long as the temperature of the circulating heating fluid flowing through the pipe 6 into the pipe 13 and through the rest of the 15 vulcanizing apparatus is below 275° F. or 305° F., as above mentioned, more or less, the parts will be in the position shown in Figs. 1 and 2 with the valve 37 open to allow communication for the fuel supply through 20 the pipe 10 and thence into the burner 9. Now, if the temperature of this circulating heating fluid passing through the pipes 6 and 13 reaches 275° F. or 305° F., respectively, for soft or hard rubber goods or 25 higher the thermostatic spring 39 will expand and move the valve 37 outwardly and close the fuel supply through the pipe 10 and remain so as long as the temperature remains at 275° F. or 305° F., respectively, 30 or above. Now, if the temperature falls below the degrees above mentioned the thermostatic spring 39 will automatically contract and bring the parts back in a position shown in Fig. 2, so that the passage is free for the 35 supply of fuel through the pipe 10 to the burner 9. The pump 3 is driven by the belt 5 operated by the electric motor 4 which is in circuit with the rheostat 48 on which is pivoted the rheostat arm 23 connected in 40 turn by the link 21 with lever 20 pivoted at 19 and connected at its outer end to the stem 18 secured to the thermostatic spring 17 of the thermostat 16. The rheostat is connected by the wires α and α' to a suitable source 45 of electricity.

To heat the interior chamber 27 of the vulcanizer 47 the circulating heated oil passes from the pipe 13 into the pipe 25 controlled by the valve 26 and thence 50 through the coils 28 and out through the pipe 29 controlled by the valve 30 into the pipe 15 where the circulating oil from the jacket 14 and the circulating oil in the coils 27 meet and return to the pump 3.

55 With the thermostat set for a maximum temperature of 275° F. or 305° F., more or less, as the case may be, for the circulating fluid, the thermostatic device 16 and the connecting parts will be in the position shown 60 in Fig. 1 with the circulating heating fluid returning through the pipe 15 passing through the thermostatic device 16 in the pump 3 and thence into the pipe 6 through the heater 8, thermostat 11 and vulcanizer 47 and then back to the pump 3 and as long

as the temperature remains below 275° F. or 305° F., more or less, as the case may be, this circulation is automatically kept up. Now if the temperature of the circulating heating fluid returning through the pipe 15 70 to the pump 3 should reach 275° F. or 305° F. or above, then the thermostatic spring 17 will expand and operate the stem 18, lever 19 and rheostat arm 22 so as to move the inner end 23 of the rheostat arm 22 upwardly, throwing in more resistance and stopping the motor, thereby saving power until the temperature drops below the predetermined maximum point. In such a case, if the temperature of the circulating heating fluid passing through the thermostat 16 80 should drop below 275° F. or 305° F., as the case may be, then the inner end 23 of the thermostatic arm 22 will drop back over the contact points of the rheostat 48 and cut out 85 the resistance and restart the motor so as to operate the pump 3 to its full capacity for circulating the circulating heating fluid. This operation of circulating the circulating heating fluid will be automatically kept up 90 by the pump 3 as long as the temperature of the circulating heating fluid remains below the temperature required, 275° F. or 305° F., as the case may be, in this class of apparatus.

In this class of apparatus as long as the temperature remains below the predetermined maximum temperature, say 275° F. or 305° F., suitable for the articles being vulcanized, then the pump 3 is kept in operation to keep up the circulation of the circulating heating fluid, but if the temperature of the circulating heating fluid reaches 275° F. or 305° F. or above, then, as above described, the motor stops, and the pump is 100 shut down so that the circulation of the circulating heating fluid through the vulcanizer 47 is cut off until the temperature of the circulating heating fluid falls below a predetermined maximum point, say about 275° 105 F. or 305° F., as the case may be, when the operation is repeated.

Instead of entirely stopping the motor 4 and the pump 3 when the temperature reaches a predetermined maximum point, say 115 275° F. or 305° F., as the case may be, the rheostat may be so arranged as to slow down the motor 4 and pump 3 so that there will be a slow circulation of the circulating heating fluid through the vulcanizer 47, but with 120 the fuel supply to the burner cut off at this predetermined point the temperature cannot be maintained at this predetermined maximum point but will automatically drop below 275° F. or 305° F., as the case may be, 125 and the pump 3 and motor 4 will be automatically speeded up for the normal circulation of the circulating heating fluid through the apparatus and at the same time when the temperature of the circulating 130

heating fluid drops below 275° F. or 305° F., as the case may be, the supply of fuel will again be admitted to the burner 9.

In this apparatus the oil used as the circulating heating fluid has a boiling point above 212° F. and may be heated to a high temperature, say 300° F. or higher, with a negligible pressure, say 5 to 10 lbs. to the square inch, which pressure is due not to the temperature of the circulating heating fluid, but to the friction due to the flow of the oil through the pipes and other parts of the apparatus, and this frictional pressure escapes to the atmosphere through the expansion tank 1 which relieves this pressure in the system. By the use of this circulating heating fluid there is produced high temperatures and low pressure, as above stated, while in the use of steam as a circulating heating fluid the high temperatures, say 250° F. to 300° F., carry high pressures, which are a source of danger, and a menace in the hands of careless workmen, with the attendant difficulty of keeping the steam joints tight.

The circulating pump is employed to keep this circulating heating fluid in constant motion and in its transit it is brought into contact with high temperatures such as would be produced by burning fuel oil, kerosene, gas or other suitable heat producing material, and this circulating heating fluid is advanced or pushed forward by the circulating pump and the heat units stored in this heating fluid medium are transferred from the heating medium to the article being vulcanized.

By this forced or accelerated circulation of the heating oil, new surfaces are more frequently presented to the heat producing device and thereby high temperatures are more economically used in the production of the heat units, and further by this circulation the circulating heating oil is prevented from becoming over heated or carbonized, and because of its velocity there is a uniform flow of heat to all the superficial area of the heating surfaces which give off a uniform heat to the material under treatment.

The advantage of this continuous circulation consists in using a heating fluid medium which does not condense at a low temperature and does not concentrate the heat because the heat units stored in the circulating heating fluid are under control and the temperature of the circulating heating fluid at no time reaches a point with injury to the article subjected to the proper degree of heat.

The great advantage in using a circulating heating fluid having a higher boiling point than water lies in the fact that by this means heat can be conveyed without vaporization and it is possible to get higher tem-

peratures than it is practical and safe to get with steam. The further advantage of using a fluid with a high boiling point is that more heat units are stored and delivered in a given time without condensation loss, also the freedom from excessive pressure removes the danger attending the use of steam as a heating fluid medium.

In this apparatus embodying my invention, there is an automatic regulation of the fuel supply to the burner and an automatic regulation of the circulation of the circulating heating fluid both controlled by the temperature of said circulating heating fluid, or any suitable hand operated controlling devices may be used to regulate the degree of temperature required, to obtain the best results.

This circulating heating oil used as a heating fluid medium in this system has a boiling point above 212° F. and also a carbonizing point higher than the temperature required to properly dry the article under treatment, so that in its circulation it imparts to the article under treatment heat at high temperatures without gasifying, as in the case of steam, and to impart temperatures higher than is practicable with steam, thereby enabling the said circulating heating oil medium to be heated to high temperatures without carbonization and the consequent deposit of carbon on the inner surfaces of the conduit. Such deposits of carbon on the interior of the heating conduit or coil prevent the easy flow of the heating oil and the ready transmission of heat to the article under treatment on account of the obstruction in the conduit by the carbon deposits and of the increased density of the circulating heating fluid by the forming of carbon in the circulating heating oil, and the integrity of the heating coil or conduit by such deposits of carbon is endangered because the heat generated by the external heater is not readily accepted by the circulating heating oil medium and thereby causes a burning or crystallizing of the heating conduit or coil, all of which difficulties are obviated by the use of a circulating heating oil whose carbonizing point is higher than the temperature required for the proper heating of the article under treatment.

In practice by this system no material loss of this circulating heating fluid medium of high boiling point and high carbonizing point occurs, as the temperature at which vaporization would take place is not approached and the circulating heating fluid medium being a non-elastic liquid differs from a condensable elastic fluid like steam and may be used over and over again for heating the material under treatment.

While I have disclosed my invention as employed in a vulcanizing apparatus as

herein described and shown in the drawings yet it will be understood that it may be applied to other heating devices used in the treatment of rubber.

- 5 While temperatures for soft rubber goods of 255° F. to 275° F. or 280° F. and for hard rubber goods from 275° F. to 305° F. have been found in practice to produce excellent results in vulcanization, yet any other 10 temperatures found suitable for the goods under treatment may be employed and the thermostatic devices accordingly set.

15 After the goods for vulcanization are placed within the chamber 27 the door 31 is closed and secured firmly in position in any suitable manner to form an air tight chamber 27 during the vulcanization of the rubber goods.

20 In starting up the apparatus the oil in the system may be cold and viscous and it requires a great pump pressure to start the circulation of the heating fluid medium, so that in case undue pressure is exerted by the pump, the pipe 40 will take care of such 25 pump pressure and allow the overflow back into the expansion tank 1 and thus relieve this pump pressure from the rest of the system until the circulating fluid is heated, after which the pressure is slight and not 30 due to the temperature of the heating oil, but is only due to its friction in flowing through the pipes. The pipe 40 may be flexible if necessary, so as to vary the heat pressure due to the pump, that is, for instance, 35 if there is a working pressure of 20 lbs. in the system due to the pressure of the pump by lowering the flexible pipe 40, the pressure could be reduced to say 15 lbs., or by raising the flexible pipe the pressure 40 could be increased as desired.

The vulcanizing chamber is provided with a suitable pressure gage 36, relief valve 35 and suitable thermometer 34.

45 What I claim as my invention and desire to secure by Letters Patent of the United States, is:

50 1. In a vulcanizing apparatus, a closed chamber for the articles to be vulcanized, a heating fluid supply, a continuous conduit for receiving said heating fluid and through 55 which said heating fluid is circulated to transmit its heat by radiation to the articles being vulcanized, means for circulating said heating fluid through said conduit, means for heating said heating fluid circulating through said conduit, and automatic means for controlling the circulation of said circulating heating fluid through said conduit.

55 2. In a vulcanizing apparatus, a closed 60 chamber for the articles to be vulcanized, a heating fluid supply, a continuous conduit for receiving said heating fluid and through which said heating fluid is circulated to transmit its heat by radiation to the articles

being vulcanized, means for circulating said 6 heating fluid through said conduit, means for heating said heating fluid circulating through said conduit, and automatic means for controlling the circulation of said circulating heating fluid through said conduit 70 by the temperature of the said heating fluid circulating within said conduit.

3. In a vulcanizing apparatus, a closed chamber for the articles to be vulcanized, a heating fluid supply, a continuous conduit 75 for receiving said heating fluid and through which said heating fluid is circulated to transmit its heat by radiation to the articles being vulcanized, means for circulating said heating fluid through said conduit, means 80 for heating said heating fluid circulating through said conduit, a motor for operating said fluid circulating means, and motor controlling mechanism for regulating the circulation of said circulating heating fluid 85 through said conduit.

4. In a vulcanizing apparatus, a closed chamber for the articles to be vulcanized, a heating fluid supply, a continuous conduit for receiving said heating fluid and 90 through which said heating fluid is circulated to transmit its heat by radiation to the articles being vulcanized, means for circulating said heating fluid through said conduit, means for heating said heating fluid 95 circulating through said conduit, a motor for operating said fluid circulating means, and automatic motor controlling mechanism for regulating the circulation of said circulating heating fluid through said conduit. 100

5. In a vulcanizing apparatus, a closed chamber for the articles to be vulcanized, a heating fluid supply, a continuous conduit for receiving said heating fluid and through which said heating fluid is circulated to 105 transmit its heat by radiation to the articles being vulcanized, means for circulating said heating fluid through said conduit, means for heating said heating fluid circulating through said conduit, a motor for operating said fluid circulating means, and automatic motor controlling mechanism for regulating the circulation of said circulating heating fluid through said conduit and controlled 110 by the temperature of the said heating fluid 115 circulating within said conduit.

6. An apparatus for treating articles by heat comprising a chamber to inclose said articles and a body of air, a continuous conduit extending into said chamber, means 120 to heat a portion of said conduit, and a mechanically propelled heat medium in said conduit.

7. An apparatus for treating articles by heat comprising a chamber to inclose said 125 articles and a body of air, a continuous conduit extending into said chamber and exterior thereof, means to apply heat to a

portion of said conduit exterior of said chamber, a viscous heat carrying medium completely filling said conduit and adapted to retain its normal condition under any 5 temperature to be utilized in said chamber, and a pump connected with said conduit and

adapted to propel said heat carrying medium through said conduit.

In testimony whereof, I have signed my name to this specification, this 13th day of 10 July, A. D. 1915.

WILLIS C. MERRILL.
